UNITED STATES PATENT OFFICE.

MOSES BEAL, OF ELYRIA, OHIO.

DERRICK.

SPECIFICATION forming part of Letters Patent No. 531,249, dated December 18, 1894.

Application filed February 6, 1893. Serial No. 461,096. (No model.)

To all whom it may concern:

Be it known, that I, MOSES BEAL, a citizen of the United States, residing at Elyria, in the county of Lorain and State of Ohio, have invented certain new and useful Improvements in Derricks; and I do hereby declare the following to be a full, clear, and exact description of the invention, such as will enable others skilled in the art to which it appertains to make and use the same.

My invention relates to improvements in derricks, and it consists in the details of construction, and in the combination of parts hereinafter described and pointed out definitely in the claims.

In the drawings, Figure 1 is a side elevation of my improved derrick. Fig. 2 is a plan view of the same. Fig. 3 is a vertical sectional view of the lower part of the post and surrounding parts. Fig. 4 is a vertical sectional view of the upper part of the post and the parts adjacent thereto; and Fig. 5 is a plan view of a modified form of the mechanism for turning the main post.

Referring by letters to the several parts, A represents a tubular post, which is secured in a socket in the plate B. As shown, the plate B is composed of two parts b and b', which are bolted together,—but it is immaterial whether it be composed of one or more pieces. Projecting downward from the plate B is a cylindrical neck, which enters a similarly shaped hole in the base plate E, which as shown, is secured to the movable frame which supports the motor and other parts of the operating machinery.

C represents the guy plate, which is provided with a hollow cylindrical stem c. The guy plate is pivoted to said upper end, the stem c entering the top of the post A. The guy plate, being itself held by guy ropes, holds the post upright, but the post is permitted to revolve about a vertical axis.

A collar D is shrunk on to, or is otherwise rigidly secured to the upper end of the post A. It is in the form of an inverted cup at its upper end, and forms the race way for a series of friction balls, the portion thereof which does so rest being approximately cone shaped. A series of friction balls is also introduced between the plates B and E, the latter being provided with an annular groove,

the former with a cone shaped formation, to form the race way for said balls. The ball bearings at the top and foot of the post A 55 greatly reduce the friction incident to turning the post on its axis.

Projecting upward from the guy plate C, are the two ears c', to which the sheave c² is journaled, one edge of said sheave being 60 approximately in line with the axis of the post A.

The boom G is pivoted to the plate B. A collar g is shrunk on or otherwise secured to the post A, near the top thereof, and to this 65 collar the brace g' is pivoted. The lower end of this brace is connected with the boom by a pin g² which passes through holes in both the boom and brace. Both of these parts are provided with a series of holes, any of which may 70 be used for the described purpose, whereby the angle of the boom to the post A may be varied at will. Above the point at which the boom is connected with the post A, said post is slotted. A sheave d passes through this slot; 75 and it is pivoted to a collar d', which is rigidly secured to the post. The outer end of the boom G, carries a sheave g³. The hoisting rope passes over the sheave g³, under the sheave d, over the sheave c² and down to the 80 hoisting drum. To turn the post on its axis, suitable mechanism is provided which is operated by the contact of two friction wheels, whereby, when the connection between the motor and the post is first made, the post will 85 begin to move very slowly, owing to the slipping of the friction surfaces, thus preventing jar and undue strain.

In the form of the device shown in Figs. 1 and 2, a circle J, or segment of a circle, is secured to the plate B. Mounted on the supporting frame is a shaft K, to which are rigidly attached two sheaves k k'. Mounted on this shaft and secured thereto by a tongue and groove connection, is a longitudinally 95 movable friction wheel, having on its edges two oppositely beveled surfaces. Secured to the driving shaft M is a co-operating friction wheel I, with which the friction wheel L may be caused to engage on either side of the axis 100 of said wheel I, as the wheel L is moved in one direction or the other by the fork lever l. This fork lever is pivoted to some fixed support, and engages in an annular groove in the

hub of the friction wheel L. A rope, cable or chain N is secured to the front edge of the circle J. It extends in a groove in said circle in opposite directions from its point of connection thereto, and its ends are secured to and wound in opposite directions upon the two drums k k' respectively. When the friction wheels I and L are in contact, the shaft K is revolved in one direction or the other as the case may be. This causes one end of the rope N to be wound up on its sheave, when at the same time the other end of the rope is unwound from its sheave. The winding up of one end of the rope causes the post A to turn about a vertical axis.

A modification of the friction device for turning the post is shown in Fig. 5. On the under side of the plate B, a beveled gear b³ is secured, which meshes with the beveled gear t, on the end of the shaft T. This shaft is mounted in suitable bearings on the frame which supports the other parts of the device. On the opposite end of the shaft T, a friction wheel t' is secured, which lies between the two flanges p p' on the sliding sleeve P. This sleeve is mounted on the driven shaft R, and is connected thereto by a tongue and groove. It is moved by a fork lever S in either direction, so as to bring either flange p or p' into contact with the friction wheel t'. When one of these flanges is in contact with the wheel t', the shaft T is revolved in one direction. When the other flange is in contact therewith, the shaft is revolved in the other direction, the post being revolved in both cases.

Having described my invention, I claim—

1. The combination of a fixed base-plate E, a fixed guy plate C having a central vertical

hole, a hollow vertical post A which is mounted at its upper and lower ends respectively in said base plate and guy plate, whereby said post is adapted to rotate upon its vertical axis, said post having a slot near its lower end, a sheave c² mounted on the guy plate, a 45 sheave d mounted on the post and projecting through the said slot therein, with a boom pivoted to said post, a collar g secured to said post, a brace g' pivoted to said collar, means for adjustably connecting said brace and boom, a sheave g³ on the end of said boom, and a hoisting cable passing over the sheaves g³, d and c², substantially as and for the purpose specified.

2. The combination of a fixed base plate E, 55 having a cylindrical opening, a plate B having a cylindrical neck which enters said opening, and ball bearings between said two plates whereby the plate B may turn upon a vertical axis, a hollow vertical post secured to said plate B having a slot near its lower end, a collar D rigidly secured to the upper end of said post, a fixed guy plate C having a tubular cylindrical stem which enters the upper end of said post, ball bearings between the 65 collar D and guy plate C, a sheave mounted on the guy plate extending over to near the axis of the post, a sheave mounted on the post and projecting through the slot therein, a boom carried by said post, and mechanism 70 for moving said post upon its vertical axis, substantially as and for the purpose specified.

In testimony whereof I affix my signature in presence of two witnesses.

MOSES BEAL.
